OSCAR C. RIXSON, OF NEW ROCHELLE, NEW YORK.

LOCK.

1,316,326.

Specification of Letters Patent. Patented Sept. 16, 1919.

Application filed November 27, 1918. Serial No. 264,358.

To all whom it may concern:

Be it known that I, OSCAR C. RIXSON, a citizen of the United States, residing at New Rochelle, in the county of Westchester and 5 State of New York, have invented certain new and useful Improvements in Locks, of which the following is a full, clear, and exact description.

This invention relates to door locks and 10 its primary object is to provide a lock, which, while possessing the characteristics of a latch lock, will also have the advantages of, a "dead lock." The construction and operation of my improved lock will be described 15 with reference to the accompanying drawings, in which:

Figure 1 is a side elevation of the lock with one of the casing plates removed and showing the face plate in section;

20 Fig. 2 is a section of the lock along the line $x-x$ of Fig. 1;

Fig. 3 is a section along the line $y-y$ of Fig. 1;

25 Fig. 4 is a section along the line $z-z$ of Fig. 1;

Figs. 5, 6 and 7 are detail views of parts of the lock;

Fig. 8 is a face view of the striker plate;

Fig. 9 is an end view thereof;

30 Fig. 10 is an edge view of the face plate of the lock showing its relation to the strike plate; and

Figs. 11, 12 and 13 are partial views of the lock showing the mechanism in different 35 stages of its operation.

The lock is represented as an ordinary mortise lock, but it will be understood that the lock may be mounted against the face of a door, as well as within its frame. The 40 lock casing comprises the usual rectangular structure having the two side plates 1 and 2 spaced apart by a surrounding edge flange 3, and a face plate 4 which, when the lock is in position, faces the jamb of the door and 45 is opposed by the strike plate secured to the jamb of the door. Projecting through a suitable orifice in the face plate 4 is a cam or strike actuated member 5 pivotally mounted in the face plate on the pin 6 and 50 adapted to be forced inward by the engagement of its surface 7 with the lip of the strike as indicated in dotted lines in Fig. 3. A stop pin 8 limits the outward movement of the cam. Inside of the lock casing the 55 heel of the cam bears against a roller 9 which

is carried by the end of a lever 10 pivoted upon a stud 11 projecting from the side of the casing. The lever extends beyond its pivot approximately three times the distance of the roller from the pivot so that the stroke 60 of the end carrying the roller is approximately one-third of that of the opposite end. This leverage, however, is subject to change as may be required. A spring 12 bears against the roller with a tendency to force 65 the latter against the heel of the cam and thus hold the cam in its outermost position.

The bolt of the lock is indicated by 13; it is rectangular in shape and normally occupies an opening in the face plate, and in its 70 retracted position is flush with the face plate. The bolt is provided with two tail rods 14 and 15 firmly fixed thereto and extending rearward and parallel along nearly the entire depth of the lock, and at their extremities are firmly connected together by a cross plate 16 which is adapted to move between two guiding flanges 17 and 18 formed upon one of the side plates of the casing. The bolt, tail rods and cross plate, 75 form a single structure adapted to move outward and inward together, the outward movement being limited by a lug 19 projecting from one of the side plates, against which the cross plate 16 strikes. The tail 80 rod 14 is surrounded by a coiled spring 20 which bears at one end against the rear face of the bolt 13, extends along the full length of the rod and rests at its other end against a fork 21 which embraces the rod and forms 85 an extension from a loose link 22 provided with a slot 23. This spring is inserted under slight compression so that it normally holds the fork 21 against the cross plate 16. The free end of the lever 10 carries a pin 90 95 24 which projects into the slot 23 of the link and has free play along the same. Thus the spring 20 by acting upon the pin 24 through the link 22, normally augments the spring 12 in holding the cam 5 in its outermost position. It will be seen that since the spring 20 is exerting its normal tension in opposite directions upon the bolt structure, it has no effect to move the bolt in either direction. The tail rod 15 is also surrounded by a coil 100 spring 25 which, at its rear end, rests against the cross plate 16 and at its forward end rests against a fork 26 which embraces the rod and is attached to a plate 27 having the shape of a bell crank, being pivoted upon 105

the stud 11 to which lever 10 is also pivoted and in front of the latter to serve as a washer therefor, and with its free end resting against a pin 28 fixed to the side plate of the 5 casing. This bell crank does not act as such, and has no motion whatever, but affords a convenient way of furnishing a fixed stop for the front end of the spring 25. This spring is also normally under 10 slight compression, but it is considerably weaker than the spring 20; its normal tension being exerted against the cross plate 16 serves to hold the bolt structure firmly in its retracted position.

15 Ordinary means are provided for dead locking the bolt, consisting of the pawl 29 pivoted on a cross stud 30 near the center of the casing and with its forward end normally pressed against the under 20 side of the bolt by a spring 31. This pawl is provided with a rearwardly projecting arm 32 having a cam surface adapted to be engaged in a manner hereinafter explained, to raise the arm 32 and throw the 25 forward end of the pawl downward. The bolt is provided with a shoulder 33 which is engaged by the pawl when the bolt has been projected its full distance to thereby dead lock the bolt until the pawl is released. 30 Projecting upward from the pawl at a point near the pivot, is a lug 34 which is adapted to be engaged by a corresponding lug 35 formed upon the lever 10. This engagement takes place only when the lever moves 35 to a position approximating that shown in Fig. 1, and under circumstances to be hereinafter described.

For retracting the bolt, either by means 40 of a key or the door knobs, there is provided the usual lever 36 pivoted at 37 and held normally in a forward position by a spring 38. A rearward movement of this lever causes it to strike and move the cross plate 16. The knob spindle, which is not 45 illustrated, but which is understood to be of the two-part type with its sections swiveled together, passes through the usual two-part hub 41, 42 which are turned in either direction to strike either the lug 39 or 40. These lugs are carried by an intermediate lever 42' which swings to allow lugs 39 and 40 to strike the forward edge 50 of lever 36 and move it rearward. One of the hub parts is provided with a peripheral 55 notch 43 into which a locking dog 44 is adapted to be projected when the lock is to be adjusted so that the bolt cannot be thrown by turning the knob on the outside of the door. The mechanism for throwing 60 this small bolt is also of common construction, consisting of the plunger 45 to which the bolt is connected and the head of which projects through the face plate 4 of the lock. A corresponding plunger 46 also 65 projects through the face plate and is con-

nected with the plunger 45 by a pivoted link 47 so that when one of the plungers is moved inward, the other is moved outward. My invention comprehends a device for locking these plungers so that having once been set, they cannot be tampered with while the door is closed, by using a bent wire or similar instrument, which might be passed into the space between the face of the door and the jamb and applied to the head of either plunger. This locking device consists of a lever 48 pivoted at 49 and having at its free end a triangular lug 50, which is adapted to engage with one side or the other of a correspondingly shaped, but reversed, lug 51 attached to the plunger 45. With these two lugs held in engagement face to face, the plunger is held in either its inner or outer position. In order to securely hold the lever 48 in engagement with the plunger while the door is closed, the lower end of the lever 10 is shaped at 52 to ride upon the upper curved edge of the lever 48 and, while the door is closed, rest at some point thereon so as to prevent the lifting of the lug 50 out of engagement with the lug 51. While the door is open, the lever 10, as will hereinafter appear, is in the position shown in Fig. 1 where it does not prevent the lifting of the lever 48, so that when the finger is pressed against either of the plungers 45 or 46, the triangular surfaces of the two lugs will ride upon each other and permit plunger 45 to either lock or unlock one of the hub parts.

To retract the bolt 13 by means of a key, the upper part of the casing is provided with a space 53 in which a cylinder lock is to be located, which, as usual, is provided 105 with a crank arm to be thrown by the key along the curved path indicated by the dotted line, to thereby strike the upper end of lever 36 and move it rearward. Lever 36 is provided with a pin 54 which stands 110 adjacent to the cam surface on the rearward extension 32 of the dead locking pawl 29 so that whenever said lever is thrown rearward to retract the bolt, the pin first of all engages the extension of the pawl to 115 throw the forward end of the pawl downward out of engagement with the shoulder 33 of the bolt. The actual retraction of the bolt after it has been released by the dead locking pawl, will be described in connection 120 with the operation of the lock. The bolt 55 in the upper part of the casing is a common device for securing the cylinder lock in its seat in the main lock and is not a feature of the present invention.

The striker plate 57 used in connection with the present lock is illustrated in Figs. 8 and 9 and is provided with a single orifice 56 for the reception of the bolt 13. The cam 5 engages and traverses the solid por- 130

tion of the striker plate and is held in its innermost position thereby while the door is closed.

The operation is as follows: With the door 5 opened and the lock in normal condition the positions of the various parts are as seen in Fig. 1. To close and lock the door, the door is simply swung to its closed position. In this movement the cam 5 first engages 10 the lip of the striker plate, as indicated in Fig. 3, and is forced inward thereby to substantially the position shown in Fig. 11. Upon the inward movement of the cam the roller 9 is also forced rearward which causes 15 the upper end of lever 10 to swing forward, the stroke of this end of the lever being considerably greater than that of the lower end. Link 22 is drawn forward and spring 20 is further compressed, the entire tension there- 20 of being then exerted against the bolt 13 to force it outward. The bolt responds only to the extent of engaging the solid part of the striker plate, as seen in Fig. 11, but when the door reaches its full closed position, the 25 opening 56 in the striker plate is presented to the bolt, whereupon the spring pressure behind the latter projects the bolt into the orifice to the full extent of its throw, which is determined by the cross plate 16 striking 30 the detent 19. At this time the shoulder 33 of the bolt passes beyond the end of the pawl 29 and the latter springs upward to dead lock the bolt, as seen in Fig. 12. It will be observed that as the movement of the up- 35 per end of lever 10 is considerably greater than that of the cam 5, and is also considerably more than the actual throw of the bolt, the bolt will be given its full throw notwithstanding the fact that the cam may 40 be thrust inward only a fraction of its intended normal movement by the striker plate. For this reason, notwithstanding an unusually wide space between the face of the lock and the jamb, the full throw of 45 the bolt can always be obtained. The spring 20 in moving the bolt outward further compresses the light spring 25 against the stop 26.

To unlock the door the lever 36 is swung 50 to the rear either by turning one of the knobs or by inserting and turning the key in the manner hereinbefore described. The first effect of this is to lift the rear end of the pawl by engagement between the pin 54 55 and the cam surface on the arm 32. This throws the forward end of the pawl out of engagement with the shoulder 33. Further movement of lever 36 is aided by the power stored in spring 25, but is opposed by the 60 necessity of again compressing spring 20 into the space occupied in Fig. 11, because lever 10 is held immovable by the cam which is against the striker plate. The back of the lever 36 strikes the cross plate 16 and posi- 65 tively carries the bolt structure from the po-

sition shown in Fig. 12 to the position shown in Fig. 11, where the bolt is released from the orifice 56 in the strike plate, whereupon the door can be pushed open, allowing the cam to be pushed outward under the action 70 of springs 20 and 12 and the parts to assume the position shown in Fig. 1 with the bolt structure held firmly retracted by the spring 25, and spring 20 inert.

By providing the elastic connection be- 75 tween the cam and the bolt which is afforded by the spring 20, and by providing for a multiplication of the movement between the cam and the bolt, it becomes possible to project the bolt by spring power to any extent 80 of throw as soon as the orifice in the strike plate is presented to it. Thus whatever throw of bolt may be required for security may be readily obtained in a lock of this 85 character.

By carelessness or design the cam 5 might be pushed inward while the door is open. This would result, as can be easily understood, in throwing the bolt outward to its full limit where it would become dead locked 90 by the pawl dropping into engagement with the shoulder 33. Obviously the door could not be closed with the lock in this condition and an attempt to do so might result in injury to the door or the lock. Accordingly 95 when the pressure, which forced the cam inward, is removed, the spring 20 returns the link 22 and the lever 10 rearward, until the fork 21 of the link strikes cross-plate 16 as seen in Fig. 13. At this point the spring 100 12, which before had but slight purchase upon the end of lever 10, now exerts a strong push against the roller 9 causing the lug 35 on lever 10 to forcibly strike lug 34 on the pawl and knock the latter out of engagement with the shoulder 33, the pin 24 on lever 10 meanwhile traversing slot 23. This releases the bolt which is then retracted to its normal position, seen in Fig. 1, by the spring 25, the cam 5 meanwhile going 110 to its outermost position. It is in this operation that the slot 23 in link 22 performs its function in permitting the upper end of lever 10 to swing rearward independently of the link. 115

The upright position of lever 10 as shown in Fig. 12 is the full throw position, but it will be understood that a shorter stroke due to the cam not being pushed in so far would also serve to throw the bolt its full stroke. 120 In any final position when the door is locked the lower end of lever 10 rests upon the lever 48 and locks the disabling plunger 45 in one or the other of its two positions.

I claim:

1. In a lock, the combination of a bolt, two springs acting thereon to effect movement in opposite direction, a strike actuated member arranged to store power in one of said springs to project the bolt, and means 130

whereby the movement of the bolt under such power, will put the second spring under tension to retract the bolt.

2. In a lock, the combination of a bolt 5 and two springs of different power, the stronger spring being normally inert to effect movement of the bolt while the weaker spring normally opposes the projection of the bolt, and means for applying power 10 through the stronger spring to project the bolt.

3. In a lock, the combination of a bolt, a dead locking device therefor, a normally projecting member arranged when moved 15 inward to project the bolt to its dead locked position, and means whereby the return of said member will release the dead lock.

4. In a lock, the combination of a bolt, a dead locking device therefor, a spring 20 tending to retract the bolt, a normally projecting member arranged when moved inward to project the bolt to its dead locked position, and means whereby the return of said member will release the dead lock.

5. In a lock, the combination of a bolt, a strike actuated bolt projecting member, a dead locking device for the bolt, a key or knob operated mechanism, for retracting the bolt, and means whereby either the last 30 mentioned mechanism or the said member may release the dead locking device.

6. In a lock, the combination of a knob locking plunger, a pawl for holding the same in either of two positions, and a strike 35 actuated bolt throwing mechanism adapted to engage and lock said pawl while the bolt is projected.

7. In a lock, the combination of a sliding bolt provided with a tail rod, a spring surrounding the tail rod and bearing at one 40 end against the head of the bolt, a link having a forked end embracing the tail rod

against which the opposite end of the spring bears, a strike actuated member and connections between said link and member, for 45 the purpose set forth.

8. In a lock, the combination of a sliding bolt provided with a tail rod, a spring surrounding the tail rod and bearing at one 50 end against the head of the bolt, a link having a forked end embracing the tail rod against which the opposite end of the spring bears a strike actuated member and lost motion connections between said link and member, for the purpose set forth.

9. In a lock, the combination of a sliding bolt having two tail rods, a coiled spring on each rod, a cross head connecting the tail rods together, one spring bearing against the cross-head and against a fixed support 60 while the other spring bears against the head of the bolt, and a strike actuated member against which the latter spring also bears.

10. In a lock, the combination of a bolt, 65 two springs adapted to act thereon, one spring being normally under tension to hold the bolt retracted and being of weaker power than the other spring, while said other spring is at the same time inert with 70 respect to the bolt, and a strike actuated member adapted to store power in the latter spring to overcome that of the former lighter spring to project the bolt.

11. In a lock, the combination of a knob 75 locking plunger, a bolt, a pivoted lever spring pressed in one direction and strike actuated in the other, connections whereby the bolt is thrown by the lever and means whereby the lever locks and releases said 80 plunger.

In witness whereof, I subscribe my signature.

OSCAR C. RIXSON.
